ALFORD LAMB, OF JEFFERSONVILLE, NEW YORK, ASSIGNOR TO HIMSELF,
WILLIAM H. MORSE, AND MARY E. LAYMAN.

Letters Patent No. 74,919, dated February 25, 1868

IMPROVED WASHING-MACHINE.

The Schedule referred to in these Letters Patent and making part of the same.

TO ALL WHOM IT MAY CONCERN:

Be it known that I, ALFORD LAMB, of Jeffersonville, in the county of Sullivan, and State of New York, have invented certain new and useful Improvements in Washing-Machines; and I do hereby declare that the following is a full, clear, and exact description thereof, reference being had to the accompanying drawings, and to the letters of reference marked thereon, which form a part of this specification, in which—

Figure 1 is a section in front of the roller, and

Figure 2 a transverse section.

The nature of this invention consists, first, in the employment of an auxiliary spring-bottom, in combination with a strip of India rubber, and second, in the employment of a fluted roller, in combination with a strip of India rubber, or its equivalent, when used substantially in the manner hereinafter specified.

To enable others skilled in the art to make and use my invention, I will proceed to describe its construction and operation.

A represents a vessel, which may be a common wash-tub. B is the semicircular auxiliary bottom, which rests upon springs d d, said springs being secured to the bottom of vessel or tub A, and the auxiliary bottom B may extend or occupy about one half of the superficial measurement of the main bottom of the tub. C represents a strip of India rubber of sufficient thickness and width to offer a suitable resistance and pressure upon the clothing as it passes between said strip of rubber and the roller D. The auxiliary bottom B is provided with a groove, in which the strip of rubber is confined, or said strip of rubber may be placed on the side of the auxiliary bottom, and secured there by means of a strip of wood or metal, having screws passing through it. The roller D is fluted, and is provided with axles, which have their bearing in the tub A, in a straight line with the edge or side of the auxiliary bottom B. At one end of this fluted roller is the crank, g, by means of which it is operated. It will be remarked that the strip of India rubber should extend upward to the lower part of the roller D.

The operation of my machine is so simple as to scarcely require a description, being only necessary to fill the tub with a suitable quantity of water, and run the articles to be washed between the roller and rubber strip, which will in a short time thoroughly cleanse them without tearing or injuring them in the least.

After the washing process is complete, the clothing can be perfectly rinsed by putting them through a similar operation, the springs under the auxiliary bottom allowing said bottom to accommodate itself to the size of the article to be washed.

Having thus described my invention, what I claim as new, and desire to secure by Letters Patent, is—

The auxiliary spring-bottom B, India-rubber strip C, and fluted roller D, all arranged substantially as and for the purpose described.

In testimony that I claim the foregoing as my own, I affix my signature in presence of two witnesses.
